UNITED STATES PATENT OFFICE.

THEODOR BIERAU, OF ROTHAU, LOWER ALSACE, GERMANY.

VELOCIPED.

SPECIFICATION forming part of Letters Patent No. 358,590, dated March 1, 1887.

Application filed June 9, 1886. Serial No. 204,631. (No model.) Patented in Belgium May 21, 1885, No. 68,953; in France May 21, 1885, No. 169,081; in England May 21, 1885, No. 6,245; in Germany May 22, 1885, No. 33,670, and May 11, 1886, No. 37,805; in Italy June 12, 1885, XXXVI, 280; in Austria-Hungary November 18, 1885, No. 19,282 and No. 58,893, and in Denmark May 18, 1886, No. 292.

To all whom it may concern:

Be it known that I, THEODOR BIERAU, a subject of the German Emperor, residing at Rothau, Lower Alsace, German Empire, have 5 invented certain new and useful Improvements in Velocipedes, (for which Letters Patent have been obtained in Belgium, No. 68,953, dated May 21, 1885; in Denmark, No. 292, dated May 18, 1886; in Germany, No. 33,670, dated 10 May 22, 1885, and No. 37,805, dated May 11, 1886; in France, No. 169,081, dated May 21, 1885; in Great Britain, No. 6,245, dated May 21, 1885; in Italy, No. 280, dated June 12, 1885, and in Austria-Hungary, No. 19,282 and No. 15 58,893, dated November 18, 1885;) and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Referring to the accompanying drawings, 25 Figure 1 is a front elevation of a portion of the steering yoke or part of a velocipede embodying my improved mode of securing the steering bars or handles thereto. Fig. 2 is a side elevation thereof. Fig. 3 is a detached 30 detail side elevation, on a larger scale, of a portion of one of the steering-bars. Fig. 4 is an under side view of the same. Fig. 5 is a section on line 5 5 of Fig. 3. Fig. 6 is a like view on line 6 6 of said Fig. 1. Fig. 7 is a top 35 plan view, Fig. 8 a side elevation, and Fig. 9 a rear elevation, of the upper portion or head of the steering yoke or post, the steering handles or bars being removed therefrom, said figures being drawn to an enlarged scale. Fig. 40 10 is a rear elevation of one-half of the steering yoke or post, and Fig. 11 a side elevation of the same, showing a slight modification in the construction of the means for connecting the steering bars or handles. Fig. 12 is a section on line 12 12 of Fig. 10. Fig. 13 shows 45 by a side elevation a part of the steering-yoke and a portion of one of the steering bars or handles, the latter in longitudinal central section. Fig. 14 is an under side view of the

steering bar or handle shown in Fig. 12; and 50 Fig. 15 is a section on line 15 15 of Fig. 14, looking toward the right.

In these drawings like letters indicate like parts wherever such may occur in the drawings.

One of the objects of this invention relates to an improved means for securing the steering-bars to the steering yoke or post, so as to insure their folding together forwardly when, by reason of meeting with an obstruction, the 60 rider is thrown forward, and takes what is commonly termed a "header," so as to enable him to land on his feet.

The further object of this invention is to protect the steering-bars from injury, when 65 the machine is tilted forward with the bars folded together, and said bars brought with great force to the ground, by causing the same to fold backward onto the saddle as soon as they come in contact with the ground.

To these ends the invention consists in connecting the steering-bars to the steering yoke or post of the velocipede by a universal or ball-and-socket joint, and providing the said steering yoke or post with means whereby the 75 bars may move in the direction of the vertical axis of the yoke or post and in a direction at right angles thereto, but rearwardly only, substantially as hereinafter fully described.

The invention further consists in the means 80 for locking the steering-bars rigidly to the yoke or post for operating, and in the combination therewith of means for disengaging said bars to enable them to fold together vertically and tilt backwardly onto the saddle 85 when brought in contact with the ground in case of an accident by which the machine is thrown forward, substantially as hereinafter fully described.

In the drawings, A' indicates the head of 90 the steering-yoke, and A² a bearing-plate secured thereto by means of screws or bolts. In said head and plate are formed hemispherical recesses, which together form spherical bearings for the spherical ends of the steering-bars 95 B, and in the upper face of said plate and head is formed a right-angled groove or recess, A³, that extends to the hemispherical cavi-

ties, one half of each groove being formed in the plate A^2 and the other half in the head A' , the branch a' of the slot extending laterally and the branch a^3 rearwardly from said 5 bearings, as more plainly shown in Figs. 7, 8, and 9.

The steering-bars B have handles B' at one end and terminate at the other end in a ball or sphere, a . The bars, near their rear end, 10 are enlarged, as shown at B' , and in the under side of said enlarged portion is formed a groove, g' , that merges at its forward end into a dovetailed groove, g^2 , formed in part in the enlargement B' and in part in a bearing or 15 face plate, G , secured to one side of the enlargement by means of screws $c d e$, as more plainly shown in Fig. 3. In said dovetailed groove is fitted, so as to slide freely therein, a block, g , the forward end, h , of which is hook-shaped, and to said block is pivoted, at l , the outer bent end of a brace-rod, D , whose inner end is connected by a pivot, b , with the steering yoke or post A , said pivot being common 20 to both braces of the steering-bars B .

25 The brace-rod D are made of two sections connected together by a right and left hand threaded sleeve, D' , for the purpose of adjusting the steering-bars into proper position relatively to the head of the steering yoke or 30 post, so that said bars may be adjusted into a position for operation more or less at an angle to the vertical axis of said yoke A .

It is obvious that when power is applied to 35 move the steering-bars B in the direction of the vertical axis of the yoke the blocks g will slide toward said yoke and, entering the recess g^2 , will be disengaged therefrom, thus permitting the steering bars to be straightened out on a line with the yoke, as shown in dotted 40 lines in Figs. 1 and 2, the rear ends of said bars moving in the lateral branch, a' , of the angular groove A^3 , or recesses $a' a^3$, formed in the head and bearing-plate $A' A^2$, as above described, and when said bars are in the position 45 described they are also free to move rearwardly in the branch a^3 of said groove or recess A^3 , so that when pressure is exerted upon said bars in that direction they will be tilted backward onto the saddle S , as shown in Fig. 2.

To prevent the accidental disconnection of the steering-bars from their respective brace-rod when in ordinary use for steering the machine, and to provide means for automatically disconnecting said bars from the braces when 50 the rider is thrown forward, I employ detent-levers E , that are pivoted in the outer end of the dovetailed portion of the groove or recess $g' g^2$, the short arms of said levers being provided with hooks i , that engage the forward 55 hooked portion h of the slide-blocks g , as shown in dotted lines in Fig. 3. These levers are angle-levers, so as to project from the under side of the steering-bars at an angle thereto.

It will be readily understood that should the 60 rider meet with an obstruction, and his machine be tilted forward thereby, the steering

post or yoke A will also move with the machine forward and downward, thus bringing the projecting arms of the detent-levers on a line with the thighs of the rider, which in his 70 forward movement strike or bear on said lever-arms, the hooked end thereof moving out of engagement with blocks g , and releasing the braces D . The bars B , at the same time moving forward with the rider, will fold together, 75 and as the handles B' thereof strike the ground they will be tilted backward onto the saddle, as above described, thus enabling the rider to land on his feet, and preventing injury to the steering-handles, which would otherwise result 80 from the violence with which they are brought in contact with the ground.

When it is desired to lock the detent-levers D out of operation—that is, when it is desired 85 to hold them in engagement with the blocks g —I provide a ring, F , held in frictional contact with the steering-bar by means of spring f , which ring, when moved back toward the fulcrum of the levers E , will lock the same against rotation, as shown in dotted lines in 90 Fig. 3, and if the threaded sleeves or nuts D' are rotated to shorten the braces D , the steering-bars will be firmly locked into position.

Instead of the ring and spring, a nut working 95 on a threaded portion of the steering bar may be employed to produce the same result, as will be readily understood.

Other means may be employed for obtaining the proper movement of the steering-bars, under the circumstances referred to. For instance, a uniformly-dovetailed groove, g' , may be formed in the under side of the steering-bars and the braces connected with the sliding block and the steering yoke or post by means of universal joints, as shown in Figs. 10, 11, 100 and 12, the inner end of the braces being connected with the yoke on opposite sides by ball-and-socket joint, and with the blocks g , by a universal joint, $g^3 g^4$, of well-known construction, so as to allow the steering-bars B to 105 move first on a line with the vertical axis of the yoke or post, and then rearwardly at right angles thereto in the grooves or recesses A^3 , as shown in said Figs. 10, 11, and 12. It will be readily understood that this mode of connecting the brace-rod D to the yoke and blocks 110 may also be employed in the construction shown in Figs. 1 to 7, and with some advantage in case the blocks should fail to move out of the groove from any cause.

If desired, the enlarged portion B' of the steering-bars may be of tubular form, as shown in Figs. 13, 14, and 15, having in its under side a slot, G' , the rear end of which is of such width as to allow the sliding blocks g , which 115 may be cylindrical in cross-section, to slide out of the tubes to which the ball-bearing and steering-arms are connected at opposite ends, as plainly shown.

The detent-levers in this construction are 120 pivoted on screw-points $k k$, Fig. 14, and locked against rotation by a ring, F , one of

said screw-pivots *k* serving to receive the spring *f* that binds the ring *F* to the steering-bar.

I do not desire to claim herein certain features of construction shown, described, and claimed in my pending application for patent, Serial No. 168,985, filed June 17, 1885, except so far as such devices may enter into combination with the novel features of construction hereinabove described.

Having described my invention, what I claim, and desire to secure by Letters Patent, is—

1. In a velocipede, the combination, with the steering-yoke, of steering bars or handles connected thereto by universal or ball-and-socket joints and a locking device to lock the said bars against movement on said yoke, substantially as and for the purpose specified.

2. In a velocipede, the combination, with the steering-yoke, of steering-bars connected with said yoke by universal or ball-and-socket joints, a locking device to lock the bars against movement on the yoke, and detents to automatically disengage said bars from the locking device when pressure is applied to said detents, substantially as and for the purposes specified.

3. In a velocipede, the combination, with the steering-yoke, of steering-bars connected with said yoke by universal or ball-and-socket joints, a locking device to lock the bars against movement on the yoke, detents to automatically disengage said bars from the locking device when pressure is applied to said detents, and a locking device to lock the detents out of operation, substantially as and for the purposes specified.

4. In a velocipede, the combination, with the steering-yoke provided in its head with spherical recesses and angular grooves *H*³ intersecting said recesses, of steering-bars having ball-bearings seated in said recesses, said bars being free to swing vertically and horizontally in the branches *a* *a*³ of said grooves *a*³, and a locking device for locking the bars into operative position, substantially as and for the purposes specified.

5. In a velocipede, the combination, with the steering-yoke, of steering-bars connected with said yoke by universal or ball-and-socket joints, said bars being arranged to swing in arcs of circles at right angles to each other, a locking device consisting of brace-rods connected at one end to the yoke and at the other to a block or bearing that is free to slide in a longitudinal groove formed in said steering-arms, and means to hold the block against motion in the groove, substantially as and for the purposes specified.

6. In a velocipede, the combination, with the steering-yoke, of steering-bars connected with said yoke by universal or ball-and-socket joints, a locking device consisting of brace-rods, adjustable as to length, connected at one end to the yoke and at the other to a block or bearing that is free to slide in a longitudinal

groove formed in said steering-arms, and means to hold the block against motion in the groove, substantially as and for the purposes specified.

7. In a velocipede, the combination, with the steering-yoke, of steering-bars connected with said yoke by universal or ball-and-socket joints, brace-rods connected at one end by a universal joint to the yoke and at the other by a like joint to a block or bearing that is free to slide in a groove or recess formed in said bars, and means to lock the block against motion in the groove, substantially as and for the purposes specified.

8. In a velocipede, the combination, with the steering-yoke, of steering-bars connected with said yoke by universal or ball-and-socket joints, brace-rods connected at one end by a universal joint to the yoke and at the other by a like joint to a block or bearing that is free to slide in a groove or recess formed in said bars, and a detent-lever, *E*, operating to lock the block against movement in the groove and automatically release the same when pressure is applied to one of the lever-arms, substantially as and for the purposes specified.

9. In a velocipede, the combination, with the steering yoke or post provided in its head with spherical recesses and angular grooves *A*³ intersecting said recesses, steering-arms terminating in a ball-bearing seated in said recesses, said bars having a groove, *g* *g*³, in their under side, blocks *g*, fitted and arranged to slide in said grooves and provided with a hook end, *h*, and brace-rods connected with the blocks and yoke or post, of the detent-levers *E*, having hooked portion *i*, adapted to engage the hook end of the blocks, substantially as and for the purposes specified.

10. In a velocipede, the combination, with the steering-yoke provided in its head with spherical recesses and angular grooves *A*³ intersecting said recesses, and steering-bars terminating in ball-bearings seated in said spherical recesses in the head of the yoke and having a tubular portion, *B*', slotted in its under side, of blocks *g*, fitted and sliding in said tubular portions and provided with a hook end, *h*, brace-rods connected with the blocks and yoke, and detent-levers *E*, having a hook-arm, *i*, that engages with the hook end of the blocks, substantially as and for the purposes specified.

11. The combination, with the steering-yokes, steering-bars connected thereto by a universal joint, brace-rods *D*, adjustable as to length, arranged to slide along the bars, and detent-levers *E*, pivoted to said bars and operating to lock the brace-rods against movement, of the locking-rings *F* and springs *f*, substantially as and for the purposes specified.

In testimony whereof I affix my signature in presence of two witnesses.

THEODOR BIERAU.
